CLAIM

The ornamental design for a trailer winch as shown and described.

DESCRIPTION

FIG. 1 is a front top left perspective view showing the trailer winch.

FIG. 2 is another front top left perspective view showing the trailer winch at a different angle.

FIG. 3 is still another front top left perspective view showing the trailer winch at a different angle.

FIG. 4 is a front top right perspective view showing the trailer winch.

FIG. 5 is a rear bottom right perspective view showing the trailer winch.

FIG. 6 is a rear bottom left perspective view showing the trailer winch.

FIG. 7 is a front view showing the trailer winch.

FIG. 8 is a rear view showing the trailer winch.

FIG. 9 is a top view showing the trailer winch.

FIG. 10 is a bottom view showing the trailer winch.

FIG. 11 is a left end view showing the trailer winch; and, FIG. 12 is a right end view showing the trailer winch.

1 Claim, 10 Drawing Sheets
